UNITED STATES PATENT OFFICE

HARRY SCHLESINGER, OF DES MOINES, IOWA

FIRE-EXTINGUISHING VALVE SYSTEM

Application filed October 3, 1927. Serial No. 223,648.

The object of my invention is to provide a fire extinguishing valve system for use in buildings or the like where combustible fluids or chemicals or other extreme fire hazards are involved, the parts of the system being comparatively simple and constructed of durable material.

Another object of my invention is to provide in such a system a plurality of valves distributed at substantially equal points throughout a room and positioned below the ceiling thereof at the most effective points for extinguishing fires which may occur in the commodities or apparatus contained in the room.

Another object of my invention is to provide these valves for the controlling and releasing of a fire extinguishing element or fluid, the valves being opened automatically upon the destruction of fusible links or manually by actuation of an operator.

Still a further object is to provide each of the valves with dual means for opening it, one of these means comprising a fusible link for automatically opening the valve to which it is attached and the other means being controlled independently of the individual fusible link.

Still a further object is to connect another means for each of the valves mentioned in the last object whereby all the valves of the series may be operated or opened simultaneously by a manual control.

Still another object is to provide fusible links in the connections between the valves so that upon destruction of any one of these links, the entire series of valves may be opened automatically by a weight or other device operatively connected to the valves.

With these and other objects in view, my invention consists in the construction, arrangement and combination of the various parts of my invention, whereby the objects contemplated are attained, as hereinafter more fully set forth, pointed out in my claims, and illustrated in the accompanying drawings, in which:

Figure 1 is a horizontal sectional view through a plant or storage room or the like

wherein fire hazards are quite extreme, the section being cut just below the ceiling of the room in order to illustrate a number of valves as assembled in the system to be disclosed in this application.

Figure 2 is a vertical sectional view on the line 2—2 of Figure 1 illustrating one of the series of the valves forming a part of the system in side elevation.

Figure 3 is an enlarged plan view of one of the valves and its connections.

Figure 4 is a front elevation of the valve illustrated in Figure 3.

Figure 5 is a detail sectional view on the line 5—5 of Figure 4.

Figure 6 is an enlarged detail sectional view on the line 6—6 of Figure 4; and

Figure 7 is a sectional view on the line 7—7 of Figure 6, one position of the parts being shown in dotted lines.

In the accompanying drawings I have used the reference numeral 10 to indicate the ceiling of a plant or storage room A where fire hazards are quite extreme and 12, the floor thereof. The end walls of the room A are indicated by the reference numerals 14.

In my valve system I employ a main feeder pipe 16 for feeding a fire extinguishing element or fluid, to fire extinguishing valves B. The fire extinguishing element may be water or a chemical or may be steam, especially in plants where highly explosive or combustible fluids are used as water is not effective in extinguishing such hazards.

I have illustrated a steam boiler 18 for supplying steam to the valves B but it is to be understood that this does not limit me to the use of steam exclusively. Each valve B comprises a body portion 20 connected by a T 22 and nipple 24 to the main feed line 16. Where steam is used it is desirable to provide for the return of any steam which may be condensed and I make such provision by sloping the feed line 16 as illustrated in Figure 2 of the drawings so that water condensed in the feed line will drain into the T's 22. For dispensing with the water drained into the T's 22 I provide a drain line 26 returning through a check valve 28 to the boiler 18.

Return of this water is through a trap 30 and into a condensation tank 32 from which the water is pumped by the pump 34 back into the boiler 18.

Each fitting 20 is provided with a valve seat 36 which is closed by a valve plug 38. The valve plug 38 is held against the seat 36 by an arm 40 having a set screw connection 42 with the valve plug 38. The arm 40 is pivoted to ears 44 formed on the body portion 20 of the valve B and is held in the full line position illustrated in Figure 6 by a fusible link 46, hook rod 48, spring 50, nut 52, lever 54, and cam member 56. The cam 56 is held in position for rocking movement by a fitting 58 having a pair of ears 60 thereon and a stud 62. The stud 62 of the fitting 58 is screwed into a collar 64 which in turn is screwed onto the body portion 20 of the valve B.

The stud 62 is shouldered so that pivotal movement of the cam 56 is insured without danger of the fitting 58 binding against the cam.

The lever 54 is pivoted on a pin 66 mounted in the ears 60 of the fitting 58 and is provided with a forked end 68 adapted to receive the rod 48. The spring 50 is positioned on top of the forked end 68 of the lever 54.

The other end 70 of the lever 54 engages under the cam 56 whereby the lever itself is held in the full line position illustrated in Figure 6 by the cam 56. The fusible link 46 is secured to the lower end of the hooked rod 48 and is hooked over the free end of the arm 40.

From the foregoing construction of my valve, it will be obvious that the destruction of the fusible link 46 will allow the arm 40 to drop to the dotted line position shown in Figure 6 for removing the valve plug 38 from the valve seat 36 and thereby releasing the fire extinguishing element from the valve thus operated. Each of the valves B can be operated independently of the fusible link 46 by swinging the cam 56 to the dotted line position shown in Figure 7 so that the cam is removed from the end 70 of the lever 54 for allowing this end to raise. The forked end 68 of the lever 54 will then be lowered to allow the fusible link 46 to unhook from the arm 40 and to allow the arm 40 to drop for opening the valve.

For swinging the cam 56 of each valve unit B I provide a lever 72 having a stud 74 thereon adapted to be positioned in an opening 76 formed in the cam 56. Set screw means 78 is provided for securing the lever 72 relative to the cam 56.

In Figure 1 I have illustrated three series of valves and each series comprises four valves, the arms 72 of which are connected by link bars 75. The link bars 75 are provided with slots 77 through which rivets

79 extend. The rivets 79 extend through openings in the upper ends of the levers 72.

Between adjacent valves of each series I provide a fusible link connection 80 interposed in the line of link bars 75. Just beyond the end valve of each series I provide a weighted bell crank lever 82 extending through a slot 84 formed on the end link bars 75 by strips of metal 86 riveted to the sides of the bars as clearly shown in Figure 3. A pin 88 in the bell crank 82 insures that the end link bar 75 will at all times remain in proper position relative to the bell crank 82. A roller 90 is positioned on a rivet 92 extending through the end link bar 75 and the strip 86 for providing efficient operative connection between the link bars and the bell cranks. Each bell crank 82 is provided with a weight 94. The bell crank levers 82 are pivoted on brackets 104 which may be clamped around the feed pipes 16 or supported in any other convenient manner. A slotted bar 102 is provided and may be fixed to the ceiling or otherwise supported for the purpose of preventing undesirable side movement of the bell crank levers 82.

From the construction of the parts just described it will be obvious that fusion of any of the links 80 independent of the links 46 will cause a break in the line of link bars 75 and the weight 94 on the bell crank lever 82 at one end of the series of valves will open all valves between the link which has been fused and that bell crank. The valves on the other side of the link which has been fused will be opened by the other bell crank 82 and weight 94. In this manner I have provided an entirely automatic system whereby the valves are operated independent of each other and the entire series is operated by the fusion of one of the links between the valves. Secured to the outer end of each bell crank 82 is a chain 96 which may be utilized for manually operating the series of valves. It is desirable that the chain 96 extend to a point outside of the room as illustrated in Figure 2 and this may be accomplished in one way by providing pulleys 98 and an opening 100 in the wall 14.

Manual operation of the series of valves by the chain 96 will open each valve of the series without affecting the fusible links 46 or 80.

If found desirable each series of valves illustrated in Figure 1 may be connected together for manual operation of the entire system. Other variations such as omitting the links 80 whereby the valves are independently operated upon fusion of their respective links or the entire system is operated by hand may be arranged to suit the conditions likely to be encountered.

By the use of the system disclosed, a small fire may be put out by an individual valve but if the fire is somewhat larger and there is danger of spreading, it will fuse one of the

links 80 for operating the series of valves and thereby more effectively extinguishing the fire before it can spread.

Some changes may be made in the construction and arrangement of the various parts of my invention, without departing from the real spirit and purpose of my invention, and it is my intention to cover by my claims, any modified forms of structure or use of mechanical equivalents, which may be reasonably included within their scope.

I claim as my invention:

1. A fire extinguishing valve system comprising a series of valves for controlling a fire extinguishing element, operating means for connecting said valves together, said operating means including fusible links between adjacent valves and means for moving the operating means upon destruction of one of said links for opening each valve of the series.

2. A fire extinguishing valve system comprising a series of valves for controlling a fire extinguishing element, operating means for connecting said valves together, said operating means including fusible links between adjacent valves and weights for moving the operating means upon destruction of one of said links for automatically opening each valve of the series.

3. A fire extinguishing valve system comprising a series of valves for controlling a fire extinguishing element, an individual fusible link on each valve whereby each valve is opened upon destruction of its respective fusible link, operating means for connecting said valves together whereby movement of said operating means will open said valves, said operating means including fusible links between adjacent valves and means for moving the operating means upon destruction of one of said last mentioned fusible links for opening each valve of the series independently of the individual fusible links.

4. In a fire extinguishing system, a series of valves, fusible means associated with each valve whereby each may be independently opened for discharging a fire extinguishing substance upon fusion of its fusible means, an auxiliary means for opening all of said valves without affecting the fusible means, said auxiliary means including a plurality of fusible elements, any one of which, when fused, will allow the auxiliary means to function for opening all the valves.

5. In a fire extinguishing system, a series of valves, fusible means associated with each valve whereby each may be independently opened for discharging a fire extinguishing substance upon fusion of its fusible means, an auxiliary means for opening all of said valves without affecting the fusible means, said auxiliary means including a plurality of fusible connections extending between adjacent valves of the series whereby simultaneous movement of said connections will

open all valves of the series and means for causing such movement upon fusion of any of the fusible connections.

6. In a fire extinguishing system, a series of valves, fusible means associated with each valve whereby each may be independently opened for discharging a fire extinguishing substance upon fusion of its fusible means, a lever on each valve for opening the valve upon swinging movement of the lever and independent of the fusible means associated with the valve, a plurality of links including fusible elements connecting said levers together and means constraining to move the links in one direction, said fusible elements normally preventing such movement but allowing such movement upon fusion of any one of the fusible elements.

7. In a fire extinguishing system, a series of valves, fusible means associated with each valve whereby each may be independently opened for discharging a fire extinguishing substance upon fusion of its fusible means, a lever on each valve for opening the valve upon swinging movement of the lever and independent of the fusible means associated with the valve, a plurality of links including fusible elements connecting said levers together and weights at each end of the plurality of links and fusible elements and tending to normally stretch them.

8. A system of the character described, comprising a series of valves for releasing a fire extinguishing fluid when opened, dual means for opening said valves, one of said means comprising a fusible link on each valve whereby they may be independently opened and the other means comprising opening means for constraining all the valves toward open position and connections located between the valves for rendering such opening means ineffective, whereby all valves of the series may be simultaneously opened upon destruction of such connections, said connections including fusible links.

9. A system of the character described comprising a series of valves for releasing a fire extinguishing fluid when opened, dual means for opening said valves, one of said means comprising an individual fusible link on each valve whereby the valves are independently opened upon fusion of such links and the other means comprising mechanism for constraining all the valves toward open position and connections located between the valves to render the mechanism ineffective, said connections including each a fusible link, whereby fusion of any of such links will allow the mechanism to open the entire series of valves.

10. A system of the character described comprising a series of valves for releasing a fire extinguishing fluid when opened, opening means for constraining said valves to open position, dual means for releasing said
